UNITED STATES PATENT OFFICE.

KATHERINE V. MINEHART, OF PHILADELPHIA, PENNSYLVANIA.

COMBINED HAND-BAG AND SEAT.

1,140,997.

Specification of Letters Patent. Patented May 25, 1915.

Application filed August 19, 1914. Serial No. 857,568.

To all whom it may concern:

Be it known that I, KATHERINE V. MINEHART, a citizen of the United States, residing at Philadelphia, in the county of Philadelphia and State of Pennsylvania, have invented new and useful Improvements in Combined Hand-Bags and Seats, of which the following is a specification.

This invention has reference to hand bags, 10 and it proposes a device of that class or character which is specially designed for use both as a carrier for various small objects, and, also, as a support or rest, according as its parts are in closed or open position, respectively, so that the owner, after 15 having opened the bag and removed its contents, may dispose the bag on the ground at any desired spot, and then utilize it as a seat, in the ordinary manner.

20 The invention further contemplates certain hereinafter-described improvements in a device of the type above specified, whereby its carrying capacity, as well as its durability and general efficiency, are increased.

25 An embodiment of the invention is illustrated in the accompanying drawing, whereof:

Figures 1 and 2 are perspective views, showing the bag in open and closed positions, respectively; Fig. 3 is an enlarged vertical section of the bag in closed position; and Fig. 4 is an enlarged perspective view of a detail.

As shown in said drawing, the bag consists, primarily, of two main parts or members 1 and 2, the former of which, when the bag is open, constitutes the back of the seat, and the latter the bottom thereof. Each of these members is composed, in turn, of an 35 open, inverted U-shaped frame 3, preferably made of flat, sheet metal, and a covering 4 of canvas or other suitable textile material, the covering being disposed against the inner face of each frame and having its marginal or edge portions folded over the outer face and stitched thereto. The confronting terminals of the legs of the two frames are hinged together, as depicted in Fig. 4, being provided for that purpose with knuckles 5, 40 through which project the ends of the rod 6 constituting the pintles of the hinges. Also, the adjacent or opposite legs of the frames are connected together, toward their said terminals, by pairs of links 7, which 45 are pivotally connected, and are so arranged 50 as to form break-joints, as likewise shown

in the figure just mentioned, thereby providing collapsible braces which, when extended, serve to retain the bag members in open position. The outer ends of these links 60 are furnished with lateral pins 8, which project across the inner faces of the frame legs, and are loosely fitted in sockets 9, or the like, with which the legs are provided.

In addition to the parts above described, 65 the bag is provided with triangular side flaps or wings 10, which are made of canvas, and, as represented in Fig. 2, are preferably formed by extensions of the canvas strip or blank forming the two coverings 4 70 attached to the frames 3. These flaps fold diametrically, and, when the bag is closed and empty, project inwardly between the members 1 and 2 from opposite sides of said members. When the bag is filled, however, 75 the said flaps will be forced outward, according to the extent to which it is loaded, or to the size or shape of its contents; and when the bag is opened and extended, the flaps will straighten out and form the sides 80 of the seat. Also, the bag may be further provided with a pocket 11, which is formed by stitching or otherwise securing a separate strip of canvas or other material, along its side and bottom edges, to either of the 85 coverings 4, such strip being here shown as attached to the covering of the member 1. Finally, the outer or free upper ends of the two members are provided with suitable handles 12, which are adapted to be grasped 90 by one hand, to permit the bag to be readily carried from place to place, when closed.

The invention, its manner of use, and its advantages are believed to be apparent from the foregoing, further description thereof 95 being, accordingly, omitted.

I claim:

1. A combined hand bag and seat comprising a pair of substantially-counterpart members hinged together at their lower ends 100 for swinging movement toward and from each other to close and open the bag, one of said members forming the back of the seat and the other member the bottom of the seat when the bag is open the member forming the bottom of the seat resting directly on the ground when the members are open, inwardly folding flaps of textile material at the opposite sides of the members, and extensible connections between the adjacent 105 marginal edges of said members for holding said bag in the last-named position. 110

2. A combined hand bag and seat comprising a pair of substantially-counterpart members hinged together at their lower ends for swinging movement toward and from each other to close and open the bag, one of said members forming the back of the seat and the other member the bottom of the seat when the bag is open; flaps of textile material arranged at the opposite sides of said members and connected to the side edges thereof, said flaps folding inwardly between said members when the bag is closed, and straightening out when the bag is opened to form the sides of the seat; and break-joint devices connecting the adjacent marginal edges of said members for holding said bag in open position.

3. A combined hand bag and seat comprising a pair of inverted U-shaped metal frames having their pairs of legs arranged opposite each other and hinged together at their free ends for movement toward and from each other, each leg being provided upon its inner face with a socket; a pair of links arranged at each side of said frames and pivoted together at their inner ends, the outer ends of said links being provided with pins for reception in said sockets; a covering of textile material attached to each frame, one of the covered frames forming

the back of the seat and the other covered frame the bottom of the seat when the bag is opened, and foldable flaps connected to opposite sides of the frames, and said pairs of links and flaps straightening out when the bag is opened.

4. A combined hand bag and seat comprising a pair of inverted U-shaped metal frames having their pairs of legs arranged opposite each other and hinged together at their free ends for movement toward and from each other; a covering of textile material attached to each frame, one of the covered frames forming the back of the seat, and the other covered frame the bottom of the seat when the bag is opened, said pairs of links also straightening out when the bag is opened; and flaps of textile material arranged at the opposite sides of and inwardly foldable between said frames and connected with the coverings thereof, said flaps straightening out and forming the sides of the seat when the bag is opened.

In testimony whereof I have hereunto set my hand in presence of two subscribing witnesses.

KATHERINE V. MINEHART.
